UNITED STATES PATENT OFFICE.

HYMAN LEIBOW, OF BROOKLYN, NEW YORK.

DESIGN FOR A TEXTILE FABRIC.

Application filed March 4, 1922. Serial No. 1,049. Term of patent 3½ years.

To all whom it may concern:

Be it known that I, HYMAN LEIBOW, a citizen of the United States of America, and resident of Brooklyn, New York, in the county of Kings and State of New York, have invented a new, original, and ornamental Design for a Textile Fabric, of which the following is a specification, reference being had to the accompanying drawing, forming part thereof.

The figure is an elevation of a textile fabric showing my design.

I claim:

The ornamental design for a textile fabric, as shown.

HYMAN LEIBOW.
